COMBINED VANITY TRAY AND CABINET

Saul K. Wolff, Long Beach, N.Y.

Application December 11, 1957, Serial No. 48,867

Term of patent 14 years

(Cl. D86—10)

FIG. 2

Fig. 1 is a perspective view of a combined vanity tray and cabinet embodying my new design;

Fig. 2 is a side elevation thereof with the hinged covers in raised position.

I claim:

The ornamental design for a combined vanity tray and cabinet, as shown.
